DESIGN FOR A FACING FOR AWNING BOXES, BULKHEADS, OR SIMILAR ARTI- CLES

Morris Ketchum, Jr., New York, N. Y., assignor to
The Kawneer Company, Niles, Mich., a corpo-
ration of Michigan

Application January 22, 1945, Serial No. 117,535

Term of patent 14 years

(Cl. D13—6)

To all whom it may concern:

Be it known that I, Morris Ketchum, Jr., a citizen of the United States, residing at New York, in the Borough of Manhattan and State of New York, have invented a new, original, and ornamental Design for Facing for Awning Boxes, Bulkheads, or Similar Articles, of which the following is a specification, reference being had to the accompanying drawing, forming a part thereof.

In the drawing:

Figure 1 is a perspective view of a facing for awning boxes, bulkheads or similar articles showing my new design; and

Figure 2 is a view in end elevation thereof.

I claim:

The ornamental design for a facing for awning boxes, bulkheads, or similar articles, substantially as shown.
